Emery, Dooley, Jolley & Warren

UNITED STATES PATENT OFFICE.

WILLIAM L. THOMSON, OF NEWARK, NEW JERSEY, ASSIGNEE TO SAFETY CAR HEATING & LIGHTING COMPANY, A CORPORATION OF NEW JERSEY.

ELECTRICAL SYSTEM.

1,384,981.

Specification of Letters Patent Patented July 19, 1921.

Application filed December 14, 1916, Serial No. 136,920.

To all whom it may concern:

Be it known that I, WILLIAM L. THOMSON, a citizen of the United States, and a resident of Newark, in the county of Essex and State of New Jersey, have invented an Improvement in Electrical Systems, of which the following is a specification:

This invention relates to electrical systems, and with regard to certain more specific features thereof to systems of distribution such as are used in car lighting and the like. One of the objects thereof is to provide a practical system of the above type in which the desired efficient action is attained under different conditions of regulation. Another object is to provide apparatus of the above type which is simple in construction and in which the chance of wrong connection of the parts in use is substantially eliminated. Other objects will be in part obvious and in part pointed out hereinafter.

The invention accordingly consists in the features of construction, combinations of elements and arrangement of parts which will be exemplified in the structure herein-after described and the scope of the application of which will be indicated in the following claims.

The accompanying drawing is a diagrammatic plan of one of various possible embodiments of this invention.

Referring now to this drawing in detail, there is shown at 1 a generator which may be driven from a car axle. In the shunt field 2 of this generator there is serially connected a compressible pile of carbon disks 3, the pressure on which and consequently the resistance of which are varied as hereinafter described. Leading from one terminal of the generator 1 is a conductor 4 which is connected with the coil 5 of an ordinary automatic or main switch. This coil terminates at a contact 6 and with the switch member 7 in closed position, the circuit is continued through the conductor 8. The switch member 7 is normally spring-retracted and is attracted by a voltage coil 9 bridged across the generator terminals and held in closed position by the conjoint action of that coil and coil 5.

From the conductor 8 current is led through a storage battery 10 and current coil 11 to the conductor 12 which joins the main 13 completing the circuit to the remaining ter-

minal of the generator. Conductor 8 is also extended past the battery 10 and a current is led through a handswitch 14 and variable resistance carbon pile 15 to the lamp main 16. The carbon pile 15 is thoroughly compressed and reduced in resistance by a device here diagrammatically indicated as a bell crank lever 17 pivoted at 18 and drawn upwardly as by the spring 19. This lever is provided at its free end with a core 20, the position of which is controlled by a voltage coil 21 bridged across the lamp mains. In this manner, as there is a tendency of voltage to increase across the lamps 22, a corresponding increase of field strength of the coil 21 will rock the bell crank lever to relieve pressure on the resistance element 15 and increase the aggregate resistance thereof. This action will increase the voltage drop in the resistance element and bring the voltage across the lamps to normal value. A tendency of the voltage to fall below normal is corrected by a reverse action and hence the voltage is maintained substantially uniform.

The negative lamp main 23 leads to a pivotal point 24 on which is mounted a swinging contact lever 25. In the position of this lever shown in full lines, it makes contact with a point 26 on the conductor 27 which connects with the main 13. There are provided for contact with the swinging lever 25 a pair of contacts 28 and 29, both of which are engaged by this lever when it is swung into the position indicated in dotted lines. The contact 28 is connected by conductor 30 with the conductor running from the battery, and the contact 29 is connected by conductor 31 with a resistance element 32. The current is led from the latter element through a manually adjustable contact 33 and a conductor 34 to the conductor 12.

The pressure on the field resistance 3 is varied by a mechanism which is here diagrammatically illustrated as comprising a pair of bell crank levers 35 and 36 respectively pivoted at 37 and 38. The construction is such that the swinging of either lever may vary the pressure on and the resistance of the resistance element 3. Both of these levers are spring-retracted and tend to increase the pressure on the resistance element, and each is provided at its free end with a movable core. The core on lever 35 is

controlled by solenoid 11 and that on lever 36 co-acts with a voltage solenoid 39 connected as shown.

Considering the action of the solenoid 11 and the parts associated therewith, and assuming that at a given stage the effect of variations in the field strength of solenoid 39 is negligible, it will be seen that any tendency to variation in the current flowing in the coil 11 will remedy itself by a corresponding variation in the resistance of the element 3 and corresponding increase or diminution of the generator field strength.

Thus, with the parts set for a given operation, the coil 11 will tend to maintain in itself a substantially constant current.

With the parts in the position shown in full lines in the drawings, the coil 11 is traversed by the current flowing through the battery, and accordingly this will be maintained constant, and the lamp current when the lamps are turned on as by the switch 14, will be added to this constant value.

If, however, it is desired to maintain the entire current output of the generator substantially constant, the switch member 25 is merely swung into the position indicated in dotted lines in the drawings. With the parts in such position, the coil 11 and the shunt circuit comprising the resistance element 32, conjointly carry the total current flowing both through the battery and the lamps if the lamps are turned on. As this current will divide with a certain predetermined fraction of its total value passing through the solenoid and the remainder through the resistance 32, it will be seen that the total current will be maintained constant. This follows from the fact that if a given fraction of any quantity is a constant, the quantity itself is a constant. By suitable adjustment of the resistance 32, moreover, the amount of current flowing through coil 11 with the contact member in the position indicated in dotted lines, may be made substantially equal to that flowing through this solenoid when the switch member is in the position indicated in full lines. In this manner, no re-adjustment of the parts is required, and the solenoid with associated parts may act through their most efficient and effective range. This is of especial value in apparatus such as that herein set forth in which the generator field resistance is affected by other mechanism such as that controlled by the voltage coil 39 as the relative effect of these two solenoids is substantially unchanged.

It will thus be seen that by the mere throwing of the switch member 25, the entire system may be changed from constant battery charging current operation to constant total current operation, or the reverse. It will also be seen that not only the action but the precise range of action or effect of

action of the solenoid 11 may be held substantially constant throughout this change.

As various possible embodiments might be made of the above invention and as various changes might be made in the embodiment above set forth, it is to be understood that all matter herein set forth or shown in the accompanying drawings is to be interpreted as illustrative and not in a limiting sense.

I claim as my invention:

1. In apparatus of the class described, in combination, a generator, a storage battery adapted to be charged thereby, regulating apparatus for said generator comprising a coil, lamps adapted to receive current from said generator, means adapted to alternatively to connect said coil in a position to be traversed by current flowing to said lamps and that to said battery or in a position in which it will be traversed by the current to the battery only, and free from that to the lamps and means adapted to change the standard of action of said regulating apparatus.

2. In apparatus of the class described, in combination, a generator having a shunt field winding, a variable resistance operatively related to said field winding, means comprising a current coil adapted upon variations in the field strength of said coil to vary correspondingly the value of said resistance, a storage battery and a lamp load connected with said generator and parallel one with another, and a single device adapted alternatively to arrange said current coil in the battery branch or in series between the generator and said battery and lamps and adapted to change the standard of action of said current coil.

3. In apparatus of the class described, in combination, a generator, conducting means leading from one terminal of said generator, a storage battery, a current regulating apparatus connected in a circuit leading from said conducting means to the remaining terminal of said generator, lamps having one terminal connected to said conducting means, a conductor connected with the remaining terminals of said lamps, and means adapted in one position to connect said conductor with the last terminal of said generator and in another position to connect said conductor between said battery and said current coil and to cause said regulating apparatus to regulate at a higher standard of output.

4. In apparatus of the class described, in combination, a generator, a storage battery and lamp load connected with said generator in parallel one with another, regulating apparatus for said generator comprising a current coil, means adapted to arrange said coil either in position to be traversed by current flowing to said lamps and battery or in

the battery branch, and a circuit positioned to receive a substantial proportion of the battery and lamp current with said coil in said first position.

- 5 5. In apparatus of the class described, in combination, a generator having a shunt field winding, variable resistance operatively related to said field winding, means comprising a current coil adapted upon variations in the field strength of said coil to vary correspondingly the value of said resistance, a storage battery and a lamp load connected with said generator and parallel one with another, a single device adapted 15 alternatively to arrange said current coil in the battery branch or in series between the generator and said battery and lamps, and means rendered operative by said device adapted to shunt a substantial fraction of 20 the current about said coil.
6. In apparatus of the class described, in combination, a generator, conducting means leading from one terminal of said generator, a storage battery, a current regulating coil 25 connected in a circuit leading from said conducting means to the remaining terminal of said generator, lamps having one terminal connected to said conducting means, a conductor connected with the remaining terminals of said lamps, means comprising a 30

switch adapted in one position to connect said conductor with the last terminal of said generator and in another position to connect said conductor between said battery and said current coil, and a shunt circuit about said current coil adapted to be completed as said switch is moved into said second position. 35

7. In apparatus of the class described, in combination, a generator, conducting means leading from one terminal of said generator, a storage battery, a current regulating coil connected in a circuit leading from said conducting means to the remaining terminal of said generator, lamps having one terminal connected to said conducting means, a 40 conductor connected with the remaining terminals of said lamps, means comprising a switch adapted in one position to connect said conductor with the last terminal of said generator and in another position to connect 45 said conductor between said battery and said current coil, and a shunt circuit comprising an adjustable resistance element adapted to be completed as said switch is moved in said second position. 50

In testimony whereof, I have signed my name to this specification this 12th day of December, 1916. 55

WILLIAM I. THOMSON.
